[57] **CLAIM**

The ornamental design for a shoe sole, as shown and described.

DESCRIPTION

FIG. 1 is a bottom perspective view of a shoe sole bottom showing our new design;

FIG. 2 is another perspective view thereof;

FIG. 3 is a bottom plan view thereof;

FIG. 4 is a right side elevational view of FIG. 3;

FIG. 5 is a front side elevational view of FIG. 3;

FIG. 6 is a typical top plan view of FIG. 3, the disclosure of which forms no part of the invention;

FIG. 7 is a left side elevational view of FIG. 3; and,

FIG. 8 is a rear side elevational view of FIG. 3.
